(57) **CLAIM**

The ornamental design for a tooth cleaning device, as shown and described.

DESCRIPTION

FIG. 1 shows a first end view of the assembled device with that end being the top end according to FIG. 3;

FIG. 2 shows the opposite end view of the assembled device with that end view being the bottom end according to FIG. 3;

FIG. 3 shows a back face view of the assembled device;

FIG. 4 shows a right-side view of the assembled device according to FIG. 3 with the opposite side being a mirror image;

FIG. 5 shows a front face view of the assembled device;

FIG. 6 shows a back perspective view of the assembled device;

FIG. 7 shows a front perspective view of the assembled device;

FIG. 8 shows a front perspective view of the head for the assembled device of FIG. 1;

FIG. 9 shows an opposite front perspective view of the head with respect to FIG. 9;

FIG. 10 shows a back perspective view of the head for the assembled device;

FIG. 11 shows an opposite back perspective view of the head;

FIG. 12 shows a back face view of the head;

FIG. 13 shows a right-side view of the head according to FIG. 12;

FIG. 14 shows a front face view of the head;

FIG. 15 shows a first end view that end being the bottom top end according to FIG. 12;

FIG. 16 shows an opposite end view that being the top end according to FIG. 12;

FIG. 17 shows a side view of the handle of the assembled device shown in FIG. 4;

FIG. 18 shows a back face view of the handle;

FIG. 19 shows a first end view of the handle which is the top end according to FIG. 17;

FIG. 20 shows an opposite end view of the handle which is bottom end view according to FIG. 17;

FIG. 21 shows a front face view of the handle which is opposite the back face shown in FIG. 18;

FIG. 22 shows a back perspective view of the handle;

FIG. 23 shows a first front perspective view of the handle; and,

FIG. 24 is a second front perspective view of the handle.

The enlarged head component in FIGS. 8–16 and the handle component in FIGS. 17–24 are shown separately for clarity of illustration only.

The broken line showing of the cleaning means forms no part of the claimed design.
